UNITED STATES PATENT OFFICE.

CHARLES T. PFLUEGER, OF AKRON, OHIO, ASSIGNOR TO THE ENTERPRISE MANUFACTURING COMPANY, OF AKRON, OHIO, A CORPORATION OF OHIO.

DESIGN FOR A FISHING REEL.

Application filed March 21, 1927. Serial No. 21,234. Term of patent 14 years.

To all whom it may concern:

Be it known that I, CHARLES T. PFLUEGER, a citizen of the United States, residing at Akron, in the county of Summit and State of Ohio, have invented a new, original, and ornamental Design for Fishing Reels, of which the following is a specification, reference being had to the accompanying drawings, forming a part thereof.

In the drawings,

Figure 1 is a view of the reel looking at the front plate; and

Figure 2 is a view of the reel looking at the back plate.

Figure 3 is a plan view of the reel.

I claim:

The ornamental design for a fishing reel, as shown.

CHARLES T. PFLUEGER.
